United States Patent [19]
Woodruff

[11] **Patent Number: Des. 278,983**

[45] **Date of Patent: ** May 28, 1985**

[54] **MODULE FOR LASER WHEEL
ALIGNMENT SYSTEM**

[76] Inventor: **James L. Woodruff, 1790 Skyline
Blvd., Reno, Nev. 89509**

[**] Term: **14 Years**

[21] Appl. No.: **349,523**

[22] Filed: **Feb. 17, 1982**

[52] U.S. Cl. **D10/46; D15/199**

[58] Field of Search **D15/199; 33/288;
356/148, 152, 155; D10/46, 103**

CLAIM

The ornamental design for a module for laser wheel alignment system, as shown and described.

DESCRIPTION

FIG. 1 is a rear perspective view of a module for laser wheel alignment system showing my new design;
FIG. 2 is a top plan view thereof;
FIG. 3 is a side elevational view taken from the right of FIG. 1;
FIG. 4 is a side elevational view taken from the right of FIG. 1;
FIG. 5 is a front elevational view thereof.
